US0D1009661S

(12) **United States Design Patent** (10) **Patent No.:** **US D1,009,661 S**
(45) **Date of Patent:** **** Jan. 2, 2024**

(54) **ANALYTE MEASURING INSTRUMENT**

(71) Applicant: **BIONIME CORPORATION**,
Taichung (TW)

(72) Inventor: **Hsueh-Chuan Chang**, Taichung (TW)

(73) Assignee: **BIONIME CORPORATION**,
Taichung (TW)

(**) Term: **15 Years**

(21) Appl. No.: **29/805,991**

(22) Filed: **Aug. 31, 2021**

(30) **Foreign Application Priority Data**

Aug. 4, 2021 (TW) 110304074

(57) **CLAIM**

The ornamental design for an analyte measuring instrument, as shown and described.

DESCRIPTION

FIG. 1 is a perspective view of an analyte measuring instrument;

FIG. 2 is a front view of the analyte measuring instrument;

FIG. 3 is a rear view of the analyte measuring instrument;

FIG. 4 is a left side view of the analyte measuring instrument;

FIG. 5 is a right side view of the analyte measuring instrument;

FIG. 6 is a top view of the analyte measuring instrument; and,

FIG. 7 is a bottom view of the analyte measuring instrument.

1 Claim, 6 Drawing Sheets
